WIRE SEALING MACHINE

William King, Clapham Park, London, England

Application August 16, 1932, Serial No. 629,023
In Great Britain November 17, 1931

7 Claims. (Cl. 81—9.1)

This invention relates to improvements in wire sealing machines, and has for its chief object to provide an improved wire sealing machine for crushing and/or corrugating the wire seals described in my co-pending patent application Serial No. 629,024, filed August 16, 1932, now issued as Patent Number 1,948,719, dated Feb. 27, 1934. The sealing machine according to the present invention has, however, several advantageous features which, while rendering the same particularly applicable for use with the seals described in my co-pending patent application above referred to, at the same time enable the machine to be used with advantage with other forms of seal.

Machines for use in crushing and/or corrugating wire seals have heretofore been proposed, and they comprise briefly a wire tensioning device, a crusher, which is adapted to be forced down on to an anvil block on which the seal and wire is placed, and a cutter to sever the wire after the seal has been crushed and/or corrugated. The crusher has heretofore been in the form of a single member, and consequently the whole strain has been thrown on to the machine at once. This not only necessitates a considerable amount of labour on the part of the man using the device, but also has often resulted in deformation of the anvil block.

As compared with these prior proposals, the machine, according to the present invention, will result in a considerable saving of labour.

The sealing machine, according to the present invention, is characterized in that the crushing member is in the form of a plurality of independent crushers which are operated one after the other.

The strain is thus distributed evenly and less force and labour will be necessary to use the machine.

The operating means for the crushers, which may comprise a series of cams located above the upper ends of the crushers, are arranged preferably so that the seal is always held after it has been crushed by any one crusher until such time as the whole crushing is complete. In this way, all chance of the wire pulling out is avoided. The cams may be so arranged that one crusher is completely depressed before the following crusher commences to operate, or the second crusher may commence to operate before the first cutter has been completely depressed.

More particularly where the sealing machine is intended for use with seals such as are covered by my co-pending patent application above

referred to, i. e. seals comprising two channels each adapted to receive a wire and permanently attached to one end of the wire by being corrugated with the end of the wire therein over one half of its width, the sealing machine according to the present invention may be provided with a gripping member which is adapted to grip the seal itself prior to the tensioning operation, whereby the provision of any separate gripping member is rendered unnecessary. The crushing member is preferably in the form of a plurality of independent crushers which are operated one after the other.

The gripping member is preferably operable by the lever or handle used to operate the crushing or corrugating members.

In order that this invention may be the more clearly understood and readily carried into effect, I will proceed to describe the same with reference to the accompanying drawings which illustrate by way of example and not of limitation one convenient constructional embodiment of this invention, and in which:

Figure 1 is a front elevation of the complete machine particularly adapted for use with seals such as are described in my co-pending patent application above referred to, and

Figure 2 is a plan view of the same.

Figure 3 is a partial front elevation of the machine with the front and top cover plates removed.

Figure 4 is a section on line 4—4 of Figure 3.

Figure 5 is a section on line 5—5 of Figure 3.

Figure 6 is a perspective view showing a length of wire with a seal attached thereto ready for binding a box or case and for being sealed with the machine according to the present invention.

Figure 7 is a sectional end elevation of the machine showing the parts in the position in which the gripping member is gripping the seal.

Figures 8, A to F, are somewhat diagrammatic views showing the position of the various operative parts of the machine in their different positions throughout the operation of sealing, and

Figures 9, A and B, are views showing a modified method of operating the gripping member.

Referring now to the drawings, the sealing machine therein illustrated comprises a base *a* adapted to rest on the case to be bound, the front edge of said base being bevelled away as at *a*¹ to facilitate the withdrawal of the machine after the wire has been sealed. This base *a* is provided with an upright back plate *b* having outstanding bosses *b*¹ at its edges which extend

above the upper end of the back plate b , as at b^2 , to form bearings for a cam shaft c which extends across the top of the back plate b . Between the bosses b^1 on the back plate are arranged a cutter d and three corrugating or crushing members e , f and g , these parts being preferably of rectangular cross-section and slideable against projecting separating pieces h carried by the back plate b . Each of the members d , e , f and g is cut away as at j to receive a compression spring k , the upper end of which bears on the upper end of the cut away portion in the members, and the lower end of which bears on a pin or abutment l provided on a front cover m which takes over the bosses b^1 to enclose the sliding parts. These compression springs k thus operate to keep the upper ends of the sliding members d , e , f and g in contact with the cams d^1 , e^1 , f^1 and g^1 on the cam shaft c , one cam being provided for each member.

In addition to these sliding members, the machine is also provided with a U-shaped gripping member n which is arranged inside the flanges or bosses b^1 on the back plate b . The upper ends of this U-shaped member n also bear on cams n^1 towards the ends of the cam shaft, a compression spring n^2 being provided at each end to raise the U-shaped member n . The base of the machine a is provided with an anvil a^2 which is corrugated as at a^3 to correspond with the corrugations in the seal and also decide the shape of the corrugations to be applied to that half of the seal which is not previously corrugated.

Means are provided for rotating the cam shaft, preferably by means of a handle o which may be rocked backward and forward to drive the cam shaft c through suitable gearing o^1 and a ratchet and pawl device, not shown. This handle o may be arranged to be rocked backward and forward in a plane at right angles to the back plate, in which case it may be pivoted at one end of the back plate and drive the cam shaft through spur wheels, or it may be arranged to rock backwards and forwards in a plane parallel to the plane of the back plate as shown, in which case it may be pivoted on the back plate and operate the cam shaft through bevel pinions o^1 or wheel and worm. It will readily be appreciated, however, that the means employed to operate the cam shaft form no essential part of the present invention and consequently any other means may be employed.

At the end of the back plate b remote from the cam shaft operating handle o , the base plate a is provided with an extension a^4 which is set back from the front of the base plate (see Figure 2) and which carries a wheel p having a gapped upstanding rim p^1 , this wheel being adapted to be rotated through a ratchet and pawl device (not shown) by means of a suitable handle p^2 to tension the wire.

The bottom of the U-shaped member n is shaped to correspond to the front half of the anvil a^2 on the base plate a and the lower ends of the three corrugating members e , f and g are shaped to take into the depressions a^3 in the rear half of the anvil. Thus the gripping member is of a width or thickness equal to approximately one half of the anvil and the corrugating members e , f and g occupy the remaining space.

Describing now the operation of the device, a length of wire q (Figure 6) suitable for the case to be bound and having permanently attached thereto a seal r corrugated as at r^1 in accordance

with my said co-pending patent application is taken and the machine is placed in position on the case. The wire is then passed round the case in an anti-clockwise direction, say, and the free end is threaded through the uncorrugated half r^2 of the seal r . The seal r with the wire therein is then placed in position on the anvil a^2 with the uncorrugated half of the seal to the rear, i. e. under the separate crushing members. In this position the corrugated half of the seal will, of course, lie on the front half of the anvil under the U-shaped gripping member n . The position of the moving parts is then that shown in Figure 8A and the relative disposition of the seal and the corrugating members and the gripping members may be seen in Figure 7. The first operation is to depress the gripping member n , and this is accomplished either by the first rocking movement of the handle o or by rotating the pinion by hand, since there is, on this movement, only the pressure of the springs to be overcome. Depression of the U-shaped gripping member n is caused by the corresponding cam surfaces n^1 on the cam shaft c which are so shaped as to hold the gripping member n during the whole of the rest of the operation. The position of the parts is then as shown in Figure 8B, and it will be seen that the one end of the wire and the seal are firmly held. As the gripping member n is depressed, the shaped lower end thereof takes into the upper corrugated surface r^1 of the front half of the seal r and so, in addition to holding the seal firmly by pressing the same into the corrugated front half of the anvil, also accurately locates the seal on the anvil due to the shaping of the anvil, corrugated seal and gripping member.

After the seal has been gripped, Figure 8B, the free end of the wire q is placed across the tensioning wheel p in the slots in the rim p^1 thereof, and the tensioning handle or lever p^2 is rocked to tension the wire to the required degree. When this has been attained, the cam shaft operating handle o is actuated to rotate the cam shaft c . Now the cam surfaces d^1 , e^1 , f^1 and g^1 on the cam shaft c are so shaped that the following operation takes place. Firstly, the end corrugating or crushing member g remote from the tensioning device is forced down to corrugate the uncorrugated half of the seal r at that point, Figure 8C. When the corrugation has been effected, it will be seen that the wire q is held firmly in the seal r but the length of wire between the tensioning device and this end of the seal is placed under great tension. If, therefore, an attempt were made to corrugate the rear half of the seal at another point, the wire q would probably snap, in addition to which a very great force would be required to corrugate the wire under this tension. Consequently, I arrange for the wire to be cut between the end of the seal and the tensioning device before any further corrugations take place. This is effected by reason of the shaping of the cam d^1 which operates the cutter d and which is arranged at the end of the back plate nearest the tensioning device. After the first corrugation has been put in the seal (Figure 8C) the cutter d operates to sever the wire at the further end of the seal (Figure 8D). Further corrugation of the seal r and the wire q therein is, therefore, a simple matter as the wire q from its free end to the corrugated point (the part which now has to be corrugated) is now no longer under tension. After the cutter d has severed the wire q , therefore, the remaining

crushers *f* and *e* are depressed to corrugate the seal at the required points, these crushers operating successively (Figures 8E and F show the two stages) and corrugating the seal *r* at points progressively nearing the end of the seal at which the wire has been severed. The cutter *d* and those crushers which have served their function may remain down in contact with the corrugations which they have forced in the seal, while the other crushers operate or may be allowed to rise under the action of their springs due to the shape of the cam surfaces on the cam shaft. It is preferable, however, always to have the seal and the wire therein gripped at the rear half of the seal immediately behind the point at which any corrugating is taking place.

Due to the severing of the wire after the first corrugation, a certain amount of slip may take place of the wire in the seal during the further corrugations and consequently the power necessary to corrugate the seal will be materially reduced.

After the complete operations of gripping, corrugating and cutting (Figures 8B to F) have been carried out, the gripper and sliding members rise to free the seal, the cam surfaces being suitably shaped to secure this result, the parts thus returning to the position of Figure 8A. The machine may then be pulled away from under the wire which will snap down into position on the case.

The upper ends of all the members on which the cams bear may be provided with rollers *s* to lessen the friction and ease the operation.

If desired, one or more of the intermediate crushers may be provided at their lower ends with dies so that instead of corrugating the seal they emboss the upper surface with an initial or initials, trade mark or other desired indicia.

In this case, if the seal itself is of the type described in my co-pending patent application, Serial No: 629,024, filed August 16, 1932, now issued as Patent Number 1,948,719, dated Feb. 27, 1934, the longitudinal dividing rib in the upper surface of the seal may be discontinued in the centre to provide a flat surface to receive the mark in question from the plungers which are, of course, worked from the cam shaft as described in the specification of said patent application.

Many modifications of the above described constructional form of this invention will be apparent to those skilled in the art and such modifications may, of course, be carried into practice without departing from the scope of the present invention. More particularly do I wish to state that I do not confine myself either to the method of operating the corrugating members above described or to the relative disposition of the parts. Any suitable means of causing successive operation of the crushing members may be employed without departing from the scope of the present invention.

Also, the upwardly projecting parts of the U-shaped gripping member *n* may be disposed in recesses in the outside of the bosses or flanges *b*¹ on the back plate *b* instead of in recesses on the inside thereof.

Again, the gripping member need not be operated from the cam shaft *c* or the other means employed to operate the corrugating members.

Figures 9A and B show a suitable modified method of operating the gripping members. In this modification the gripping member *n* is 75 slideable in the bosses or flanges on the back

plate *b* as before, but the cam *n*¹ on the cam shaft *c* are dispensed with. Springs *n*² may still be provided to raise the gripper, if desired. In place of the cams *n*¹ I provide a plate *t* which is slideable backwards and forwards in suitable bearings in the bosses or flanges *b*¹ on the back plate *b*. This plate *t* projects on either side of the bosses *b*¹ and is provided with two or more inclined slots *t*¹, the lower ends of which are extended in a direction parallel with the direction of movement of the plate *t* as at *t*².

The gripping member *n* is provided with a plurality of outstanding pins *u* located one in each of the slots *t*¹. Figure 9A shows the position of the parts with the gripper raised, but it will be seen that as the plate *t* is slid in the direction of the arrow the slots *t*¹ will ride about the pins *u* and will force the gripping member *n* down to grip the seal in the manner as the same was forced down by the cams *n*¹. The pins *u* enter the straight parts *t*² of the slots when the gripper has been fully depressed, Figure 9B, and the gripper will be held down and will grip the seal throughout the following operations. After the sealing has been completed the plate *t* may be moved or knocked back to its original position to release the seal.

I claim:

1. A method of securing a tie box strap about a box or case, said tie having permanently attached to one end thereof a seal with a channel to receive the other end of the tie which consists in threading the free end of the tie through said channel tensioning the tie, corrugating the channel-part of the seal and the enclosed tie at one or more points, cutting the tie between the seal and the point at which it is tensioned and then corrugating the seal at one or more further points along the channel part.

2. A method of securing a tie box strap about a box or case, said tie at one end having permanently attached thereto by means of corrugations, a seal with an uncorrugated channel to receive the other end of the tie, which consists in gripping the seal at the corrugated part, tensioning the tie after it has been threaded through said uncorrugated channel, corrugating the channel-part of the seal and the enclosed tie at one or more points, cutting the tie between the seal and the point at which it is tensioned and then corrugating the seal at one or more further points along the channel part.

3. In a tie sealing machine of the character described, the combination of a tie tensioning device, an anvil having a corrugated profile and a cutting edge at one end, a gripper operating over a portion of said anvil, a plurality of corrugating members operating over the remaining portion of the anvil, a cutter cooperating with the edge in the anvil, and a series of cams operating together, to operate the gripper, then one or more of the corrugating members furthest from the cutter, thereafter the cutter and finally the remainder of the corrugating members.

4. A sealing machine for corrugating seals which have a corrugated part permanently attached to one end of a tie wire and a channeled part loosely attached to the other end of the wire, which comprises a corrugating member provided with a plurality of independently operable members, an anvil having its effective surface corrugated to correspond to the corrugations in the seal, a slideable gripper shaped on its

under surface to correspond to the shape of the corrugations in the seal and to press the corrugations into the depressions in the anvil, and means operating said members successively to 5 corrugate and permanently attach the seal to the loose end of the tie wire.

5. A sealing machine for corrugating seals which have a corrugated part permanently attached to one end of a tie wire and a channeled 10 part loosely attached to the other end of the wire, which comprises means for gripping the seal along the part thereof attached to the first end of the tie wire, a corrugating member provided with a plurality of independently operable 15 members, and a series of cams to successively operate said gripping means and independently operable members to first grip the seal along the portion thereof attached to the tie and thereafter corrugate and attach the seal to the loose end of the tie wire.

6. In a sealing machine, the combination of a tensioning device for a metal tie wire having one end thereof permanently attached to a seal, the other end of the tie wire being loosely embraced by the seal, a cutter to sever the tie wire, a plurality of independently operable corrugating members to attach the loose end of the seal to the other end of the wire, the corrugating members being spaced from the cutter, and means to operate one or more of the corrugating members furthest from the cutter, thereafter the cutter and finally the remainder of the corrugating members. 5

7. A sealing machine, as claimed in claim 6, 10 including a gripper operated by said means to grip the seal about the attached end of the tie wire during operation of the cutter and corrugating members. 15

WILLIAM KING. 20
